UNITED STATES PATENT OFFICE.

RICHARD GROSSKOPF, OF DRESDEN, GERMANY.

ROTARY PRINTING PRESS.

Application filed January 7, 1928. Serial No. 245,175.

My invention relates to a rotary printing press and is in its details set forth in the following description and in the annexed drawings which show by way of example a cross section of a press according to my invention, taken vertically and at right angles to the cylinder shafts.

1 is the cylinder bearing the zinc-plate, 2 the printing cylinder, 3 the rollers for transmitting the printing ink onto the zinc-plate and 4 the roller, which takes up the ink from a trough 5. The trough 5 is held by arms 6 from a shaft 7 and can be swung out, when the device is not working in order to allow 10 the rollers 3 to be lifted away from the cylinder 1 into the position shown in dotted lines where it is held by a hook 27. Carried from the same shaft 7 by arms 13 is a roller 8 the position of which is commanded by a lever 9 20 with a sliding roll 10 from a cam 11 on the cylinder shaft 12 causing the said roller to touch alternately the trough-roller 4 and roller 3 thus taking up printing ink from the former and transmitting it to the latter.

25 My invention now has for its object to allow of intermittently rotating the roller 4 in such a way, that its rotary movements can be varied in size. Each time the said roller is turned about a certain angle it offers a new 30 part of its circumference bearing fresh printing ink to the roller 8. In regulating the width of the angle of its rotary step therefore I can apply more or less printing colour to the zinc-plate according to the demands of the 35 printing process.

My invention consists in using means for accomplishing this which are very simple in construction and neither interfere with the swinging-out movement of the trough 5 nor 40 with the oscillating one of the roller 8. This is an important feature for apparatus of the kind set forth, which are to be built in small sizes. Further the controlling means are arranged in such a way, as to allow of varying 45 the size of the rotary step mentioned above without need of stopping the machine.

In accomplishing this I use sprocket wheels 14, one on the shaft of the roller 4 and one on the shaft 7, with a chain 15 running over both 50 of them and in addition a toothed disc or

ratchet wheel 16 loose on shaft 7, but fastened to the sprocket wheel on said shaft, an arm 17, also loose on said shaft, carrying a pawl or click 18 engaging the teeth of the ratchet wheel or disk 16, so that by moving the arm 17 the disc is turned by the click and with it the 55 sprocket wheels 14, which move the roller 4. The arm 17 receives its oscillating movements through the intermediary of an arm 19 from a doubled armed lever 20 journaled 60 at 21 upon the machine frame 28. The lower short arm of this lever is commanded by a cam member 22 on the commanding shaft 12 whilst the upper long arm is slotted to receive in its slot 23 the end portion of arm 19, which can 65 be clamped to the lever 20 by means of a hand screw 24 in any position along the slot 23 and will naturally impart a greater movement to arm 17 the further it is fastened towards the outer end of the slot 23. A spring 25 70 causes the free back stroke of the oscillating motion.

The lever 20 being situated near one upright of the machine frame and the hand screw 24 being placed on the outward side on 75 the said lever, it is evident, that one is able to displace the said screw during the operation of the machine and thereby to control the feed of printing colour to the zinc-plate whilst the machine is doing its work.

The driving gears on the main shaft 26 are 80 not shown.

I claim:

In a rotary printing press, the combination, with a printing cylinder, a series of rollers 85 for transmitting ink thereto, an intermittently rotatable ink take-up roller, a transfer roller oscillating between one of the aforesaid transmitting rollers and the take-up roller, an ink trough in which said take-up roller is 90 mounted on an axis so as to be swung into and out of its working position, an oscillating actuating lever, an arm pivotally and adjustably coupled to said lever, intermittent motion mechanism actuated by said arm and including a member loose on the axis around 95 which the ink-trough is to be swung out, and a sprocket drive connection between said member and the take-up roller.

RICHARD GROSSKOPF.
